(57) **CLAIM**

The ornamental design for a housing for a communication device and similar articles, substantially as shown.

DESCRIPTION

FIG. 1 is a perspective view of an ornamental design of a housing for communication device and similar articles.

FIG. 2 is a side view thereof.

FIG. 3 is a front view thereof; and,

FIG. 4 is a bottom view thereof.

The broken line portions of the drawings form no part of the claimed design or a specified embodiment thereof.

1 Claim, 2 Drawing Sheets

FIG. 1

FIG. 2***FIG. 3******FIG. 4***
